US0D1082772S

(12) **United States Design Patent** (10) Patent No.: **US D1,082,772 S**
(45) Date of Patent: ** Jul. 8, 2025

(54) **MOUNT FOR ELECTRONIC COMMUNICATIONS DEVICE**

(71) Applicant: **SPIGEN KOREA CO., LTD.**, Seoul (KR)

(72) Inventors: **Eun Mi Kim**, Seoul (KR); **Jin Yong Choi**, Seoul (KR)

(73) Assignee: **SPIGEN KOREA CO., LTD.**, Seoul (KR)

(**) Term: **15 Years**

(21) Appl. No.: **29/895,773**

(22) Filed: **Jun. 26, 2023**

(51) LOC (15) Cl. **14-03**

(52) U.S. Cl.

USPC **D14/251**

(57) **CLAIM**

The ornamental design for a mount for electronic communications device, as shown and described.

DESCRIPTION

FIG. 1 is a front, top, right side perspective view of a mount for electronic communications device showing our new design;

FIG. 2 is a rear, top, left side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines in the drawings show portions of the mount for electronic communications device that form no part of the claimed design.

1 Claim, 8 Drawing Sheets
